(57) **CLAIM**

The ornamental design for a dog toothbrush, as shown and described.

DESCRIPTION

FIG. 1 is a front and right perspective view of a dog toothbrush in accordance with the present design;

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines are for environmental structure, boundaries, or illustrative purposes only and form no part of the claimed designs to be patented.

1 Claim, 7 Drawing Sheets
